DESIGN FOR A REFLECTOR

Dwight E. Worrell, Chicago, Ill.

Application January 23, 1937, Serial No. 67,251

Term of patent 14 years

To all whom it may concern:

Be it known that I, Dwight E. Worrell, a citizen of the United States and resident of Chicago, in the county of Cook and State of Illinois, have invented a new, original, and ornamental Design for a Reflector, of which the following is a specification, reference being had to the accompanying drawing, forming part thereof. In the drawing,

Fig. 1 is a perspective view of a reflector showing my new design; and

Fig. 2 is a bottom plan view thereof.

I claim:

The ornamental design for a reflector as shown.

DWIGHT E. WORRELL.
